CLAIM

The ornamental design for a bottle, as shown and described.

DESCRIPTION

FIG. 1 is a top view of a bottle showing my new design;

FIG. 2 is a front view thereof;

FIG. 3 is a right side view thereof; and,

FIG. 4 is a bottom view thereof.

The left side view is the same as the right side view. The rear view is a mirror image of the front view.

1 Claim, 4 Drawing Sheets
